UNITED STATES PATENT OFFICE.

THOMAS B. DOOLITTLE, OF BRIDGEPORT, CONNECTICUT.

TELEPHONE-LINE.

SPECIFICATION forming part of Letters Patent No. 297,683, dated April 29, 1884.

Application filed February 21, 1883. (No model.)

To all whom it may concern:

Be it known that I, THOS. B. DOOLITTLE, of Bridgeport, in the county of Fairfield and State of Connecticut, have invented certain 5 Improvements in Telephone-Lines, of which the following is a specification.

My invention relates to an improvement in the art of telephony, which relates more particularly to the character of the supports to 10 which the line-wires are attached.

The object of my invention is the augmentation of volume and clearness of the articulation of the reproduced words.

It is well known, and has been for a long time, 15 that, although telegraphy, to be successful, demands a highly-insulated conductor for the currents employed, such is not the case with telephony. This is referred to in a lecture delivered by A. Graham Bell, October 31, 1877, 20 before the Society of Telegraph Engineers, London, in which he describes the use of the railroad-track for conversational purposes. In practice it has often been found advantageous to employ uninsulated telephone-lines, 25 and the results have been invariably favorable during the continuance of dry weather. The reason of this is not positively known, and there are among electrical experts conflicting theories upon the subject; but it has been 30 demonstrated by experience that although in dry weather the results are as indicated favorable, in wet weather the escape frequently becomes so great as to render telephonic communication difficult, and to completely prevent the electric signaling between stations 35 which is necessary to call attention prior to the transmission of a message.

The design of my invention, is specifically, 40 to obviate this drawback to uninsulated lines, and to enable such lines to work equally well in wet or damp as in dry weather; and to this end it consists in a device whereby the amount of current escaping may be limited and maintained a constant quantity, irrespective of 45 variation in the hydroscopic condition of the atmosphere. At each point of support of the telephone-wire, instead of mounting the said line-wire simply on an ordinary pin on the one hand, or upon a glass or porcelain insulator 50 on the other, I construct a grooved support-

ing device of wood in the form of an insulator and supporting-pin therefor combined, and I cover the parts of the same, which are, when in use, exposed to the atmosphere, with a water-proof paint or varnish, which is also a 55 non-conductor, with the exception of the groove where the line-wire absolutely rests.

In the drawings which illustrate my invention, Figure 1 shows a section of a telephone-line of four wires fitted with my improved device. Fig. 2 shows an elevation of the insulator-shaped supporting-pin, and Fig. 3 is a sectional elevation of the same.

In Fig. 1 a series of line-wires, *w*, are shown, extending from one pole, *P*, to another, and 65 resting on the painted wooden pins *A*, which are inserted in the cross-arms *c*.

In Fig. 2, *e* is the shank of the supporting-pin *A*, and from the shoulder *d* to the apex of the said pin the surface thereof is made water-proof by the application of a suitable paint or varnish. Between the lower part, *f*, and the upper part, *g*, of the supporting-pin is a groove, *a*, which is left unpainted. In this groove the wire is fastened in the usual way, 70 and is thus in contact with the substance of the wooden pin, and through it and the body of the cross-arm and of the pole to the earth, the pole, cross-arm, and pin composing the high resistance, which is necessary in all such 75 earth-contacts. As shown in Fig. 3, the under surface of the overhanging part *f* is made concave, the edge forming a petticoat, *b*, which aids the drip of any moisture and prevents it from continuing down the surface of the pin. 80 Were it not for the waterproofing of the surface of the support, the entire substance of the said support would in wet weather become 85 permeated with moisture, thereby acquiring a high conductive power, and thus a large proportion of the working-current would be lost by escape through the pin and down the pole; but when constructed as I have described, the pin being covered with an impenetrable waterproof and insulating-coating, maintains its 90 dry condition, and hence its electrical conducting-power remains constant and while a sufficient escape is maintained by means of the contact of the line-wire with the unpainted 95 groove, and by means of the imperfect insu- 100

lating properties of the dry wood, that escape is not exceeded, and remains uniform, keeping the line in an electrical condition similar to that of the earth, whereby retardation is prevented. The leaving of the groove *a* uncoated is of great importance where the paint or varnish used is also an insulator or non-conductor of electricity; but if the waterproofing material used be such as does not impair the conductivity of the support, the purposes of the invention will be as well accomplished if the groove be waterproofed as well as the other parts of the support.

I claim—

- 15 1. A telephone-line having a series of earth-connections of a material of low conductivity—such as wood—said material having its surface coated with water-proof material, substantially as described.
- 20 2. A telephone-line upheld by a series of supports, of wood or similar material, of low conductivity, having their surface coated with water-proof material, substantially as described.
- 25 3. A support for telephone-wires, consisting

of a wooden pin inserted in a pole or cross-arm, and made water-proof at all parts of its surface, except the point on which the conducting-wire absolutely rests, substantially as described.

4. A support for telephone-lines, consisting 30 of a wooden pin and a grooved wire-holder at its upper part, the surface of the said pin being painted or varnished, as described, to prevent the substance of the pin from acquiring moisture, and the groove thereof being left unpainted, whereby the normal escape is maintained constant, substantially as described.

35 5. A support for telephone-lines, having its surface coated or covered with a waterproofing and insulating material, except where the 40 wire rests, substantially as described.

In testimony whereof I have signed my name to this specification, in the presence of two subscribing witnesses, this 13th day of February, 1883.

T. B. DOOLITTLE.
